UNITED STATES PATENT OFFICE

132,945

DESIGN FOR AN HORS D'OEUVRE SERVER

Frank Powell, Miami, Fla.

Application April 27, 1942, Serial No. 106,728

Term of patent 3½ years

To all whom it may concern:

Be it known that I, Frank Powell, a citizen of the United States of America, residing in Miami, county of Dade, and State of Florida, have invented a new, original, and ornamental Design for an Hors d'Oeuvre Server, of which the following is a specification, reference being had to the accompanying drawing, forming part thereof,

Fig. 1 is a front perspective view of an hors d'oeuvre server, showing my new design.

Fig. 2 is a rear perspective view thereof. The face shown in broken lines is fanciful and does not represent the face of any living individual.

I claim:

The ornamental design for an hors d'oeuvre server, substantially as shown and described.

FRANK POWELL.
